UNITED STATES PATENT OFFICE.

JAMES ARTHUR DOWNHAM, OF HUDDERSFIELD, ENGLAND.

HAND STARTING DEVICE FOR INTERNAL-COMBUSTION ENGINES.

Application filed July 11, 1922. Serial No. 574,221.

To all whom it may concern:

Be it known that I, JAMES ARTHUR DOWNHAM, a subject of the King of Great Britain, residing in Huddersfield, in the county 5 of York and Kingdom of England, have invented certain new and useful Improved Hand Starting Devices for Internal-Combustion Engines, of which the following is a specification.

10 The present invention relates to an improved starting device for internal combustion engines of the type in which means are provided to avoid "back fires" of the engine being communicated to the starting crank.

15 According to the present invention the elements of an epicyclic gear are inserted between the engine shaft and the starting crank, and a free wheel clutch is mounted between the floating element of the epicyclic gear and the sun wheel, so that when 20 the hand crank is being operated the whole gear will rotate as a solid element, and should the engine shaft rotate in a contrary direction, then the epicyclic gear elements 25 will rotate round the sun wheel.

A preferred form of construction is shown in the accompanying drawings in which:—

Figure 1 is a sectional elevation.

Figure 2 is a corresponding front view 30 partly in section on the line A B of Fig. 1.

Figure 3 is a sectional elevation of a modification on the line C D of Figure 5.

Figure 4 is a corresponding end sectional view on the line E F of Figure 3.

35 Figure 5 is a part sectional front view.

The shaft 1, is provided which may be of usual form to the usual starting handle crank shaft of the engine, that is to say that it is normally detached from the engine but 40 can be slid axially to engage therewith by a one way claw coupling.

On this shaft 1, a sleeve 2, rotates freely which however can be locked with the shaft 1, by inserting a shaft or pin in the perforation 3, when it is desired to disconnect the 45 whole of the safety starting mechanism drives through the sleeve 2.

A starting crank handle 4, is securely mounted on the sleeve 2, which also carries 50 mounted radially on it a ring 5, carrying a plurality of pawls 6, engaging ratchet teeth on a disc 7, secured by studs to the casing 8. The casing 8, may be secured to a rigid part of the automobile, but it is preferred to 55 allow it a degree of rotation about its centre

against springs 9, to thereby absorb any shock.

The sleeve also has mounted on it, a sun wheel 10, meshing with planetary wheel 11, on a pin 12, sliding freely through the cage 60 13, which cage has ratchet teeth cut in it similar to the teeth on the disc 7, to co-operate with pawls 14, working in opposite sense to the pawls 6, these pawls being carried by a ring 15, also securing on the 65 sleeve 2.

On the outer end of the spindles 12, a second set of sun pinions 16, may be provided keyed thereon, or as shown, mounted on a screw threading so that they will be able to 70 rotate on the spindle 12, through a very limited angular arc before locking up against the face of the cage 13.

These pinions 16, are in constant mesh with the sun wheel 18, keyed permanently on 75 the shaft 1.

Now it will be seen that under normal starting conditions when the crank 4 is rotated, the epicyclic trains of wheel 10, 11, 16, and 18 will lock rigidly and consequently the 80 shaft 1, can be rotated. Should however, the engine back-fire, the cage 13 will be caused to rotate freely round the central axis so that the sleeve 2, will not partake in the forward rotation due to the overrunning of the 85 pawls.

The wheel 16, is allowed a certain amount of angular free movement to avoid any shock and to further avoid the possibility of the ratchets over-running when the crank 90 handle 4, is given a jerk instead of a constant thrust.

In a modified form of construction with reference to Figures 3 to 5 a starting handle 19 is mounted on a sleeve 20 which has a 95 pin 21 passing through a cam slot 22 under a sleeve 23 which has a feathered groove in it engaging with a keyway 24 secured to the casing 25. This sleeve 23 has ratchet teeth 26 on it engaging with pawls 27 on 100 the inside periphery of a pinion 28. It also carries a friction ring 29 adapted to engage with the internal surface of the casing 25 when the handle 19 is turned in a clockwise direction thus moving the sleeve 23 axially 105 along the keyway 24.

The pinion 28 meshes with a pinion 30, on a spindle 31 carried by the casing 25 and this pinion in turn meshes with a pinion 32 on a spindle 33, which pinion 32 in turn 110

meshes with a pinion 34 keyed to an extension 35 of the engine shaft 36. The purpose of the wheel 32 is to provide the correct sense of rotation throughout the gear transmission.

The casing 25 is opened at a sleeve extension 37 with pawls 38 engaging internal ratchet teeth 39 on a ball-bearing ring having arms 40 provided with torque springs 41 attached to any fixed part of the automobile vehicle. The device functions in the same manner as that of Figure 1, that is to say that a positive cranking of the engine is obtainable in a clockwise direction, but any reverse rotation of the shaft 36 merely causes a rotation of the epicyclic train about the sleeve 20.

I declare that what I claim is:—

1. A safety starting mechanism for internal combustion engines comprising a shaft connected to the engine, a starting crank, a sleeve axially revoluble on said shaft, a cage freely rotatable in one direction, a train of epicyclic wheels connecting said cage and said sleeve, a second train

of epicyclic wheels connecting said cage and said shaft; means to restrict the motion of said cage in one direction and means to prevent the rotating of said sleeve in the opposite direction.

2. A safety starting mechanism for internal combustion engines comprising a shaft connected to the engine, a starting crank, a sleeve axially revoluble thereon, a cage freely rotatable in one direction, a train of epicyclic wheels connecting said sleeve and said cage; a second train of epicyclic wheels connecting said cage and said shaft, means to restrict the motion of said cage in one direction, means to prevent the rotating of said sleeve in the opposite direction, and means to hold said sleeve from rotation.

In witness whereof, I have hereunto signed my name this 1st day of July, 1922, in the presence of two subscribing witnesses:

JAMES ARTHUR DOWNHAM.

Witnesses:

FITZGERALD M. JONES,
JOHN McLACHLAN.
